TRAP

Frank Doverspike, Washington, D. C.

Application October 5, 1943, Serial No. 505,073

4 Claims. (Cl. 43—97)

The invention here disclosed relates to traps, particularly for catching rats and mice and is in the nature of an improvement on the trap covered in the Doverspike Patent 2,304,555 of December 8, 1942.

In the patent referred to, a spring jaw is provided having a coil portion located in a channel at the foot of an upright attached to a base and this spring jaw is held open by a detent mounted on the upright and held by a trigger which is releasable by a pan or platform overstanding the base. A safety catch is provided to prevent accidental release of the detent.

The present invention relates to improvements in the attachment of the upright to the base, the mounting of the spring jaw, the trigger and safety catch construction and adaptation of the spring jaw to insure catching of either larger or smaller size animals.

Objects of the invention are to facilitate assembly, reduce the cost of parts, provide a stronger and more rugged construction, to enable easy and quick changeover from the active to the safety position and to insure that in changing over from safety to active condition, the trap will not be accidentally sprung.

Various other objects and desirable results actually accomplished by the invention will appear in the course of the following specification.

The drawing accompanying and forming part of the specification illustrates a present practical commercial embodiment of the invention. Structure however may be modified and changed within the true intent and broad scope of the invention, all as hereinafter defined and broadly claimed.

Fig. 1 is a vertical sectional view showing the trap in set condition, this view being taken as on substantially the plane of line 1—1 of Fig. 2.

Figs. 2 and 3 are back views, illustrating respectively the safety and the active positions of the detent and trigger.

Fig. 4 is a top plan view of the trap in sprung condition.

Figs. 5 and 6 are enlarged broken cross-sectional details on substantially the planes of lines 5—5 and 6—6 of Figs. 2 and 3 respectively.

Fig. 7 is a broken sectional detail of the trigger and detent in the holding and tripped relations.

Fig. 8 is a broken sectional detail illustrating the trigger in the active and safety positions, this view being taken as on line 8—8 of Fig. 7.

The base, which may be a panel of wood, is indicated at 10, and the upright is designated 11. The latter may be a piece of sheet metal and spe-

cial features of it are an angularly bent bottom flange 12, and spaced above that in parallel relation, angularly bent straps 13, engaged over the bottom and the top of the base and secured in such fashion by rivets or other through fastenings 14. The straps 13 are shown in Fig. 2 as produced by cutting out integral strip portions of the upright and bending them forward, thus leaving the openings 15. Secured by fastenings 14, the angularly bent portions 12 and 13, form in effect a clamp construction rigidly securing the upright braced in upstanding relation at the end of the base and it will be noted in Figs. 1 and 4, that this clamp construction is secured to the base in a manner to offset the upright away from the end of the base, to leave a space or channel 16, extending across the end of the base, at the foot of the upright.

The purpose of the transverse channel 16, is to provide a seat and holder for the coil portions 17 of the spring jaw and which are shown located in said channel between the end of the base, the opposing portion of the upright wall, the bottom flange 12, and the top straps 13. These parts securely confine the coils without restricting or interfering with their spring action. The ends of the coils are shown projected beneath the base at 18, where they are held by the bottom flange 12, and the loop or bail portion 19, connecting the coils, forms the jaw of the trap.

The detent for holding the jaw in open position is shown as a lever 20, having a loop 21, pivotally passed through an opening 22, near the top of the upright and terminating in a forwardly projecting angled end 23, forming a catch engageable 35 inside the bail when the latter has been raised to the upright position indicated in Fig. 1. The detent lever thus is supported to hang down over the back of the upright 11, into position where its lower end can be caught by the trigger hook 24, projecting from the trip pan or platform 25. The latter as indicated in Fig. 1, is shown as having a downwardly angled edge 26, resting on the base; the platform being confined in this loosely pivoted relation on the base by pins or brads 27, passing freely through openings provided in the plate 25.

To enable the trigger being utilized for safety catch purposes, it is shown as pivotally secured on the platform by a rivet or equivalent fastening 28, and as adapted therefore to be shifted from a position in line with the vertical portion 29, of an inverted L-shaped slot in the back, into line with the upper horizontally extending portion 30, where it will be supported against any releasing movement.

Figs. 2 and 5, show the lower end of the detent lever 20, caught and held by the trigger lever 24, and the latter shifted over into position above the lateral supporting shoulder provided by the horizontally extending portion of the slot. In such position, it is impossible to release the detent by downward pressure on the platform and the trap may then be safely handled and shifted about to locate it in the most favorable position.

To set the trigger in active position, that is, over the vertically extending portion 29, of the slot, a special setting lever is provided, indicated at 31, pivotally hung on the back at 32, and extending down past the end of the safety shoulder at 30, so that it may be swung to push the trigger from over this shoulder into position above the vertical portion of the slot—that is, to shift the trigger from the dotted line to the full line position, Fig. 8.

To avoid the possibility of accidental release when shifting the trigger off the safety shoulder, the swinging lever is shown as having a bent lower end 33, inclined to effect a lifting engagement with the trigger, as said lever is swung over from the Fig. 2 to the Fig. 3 position. This incline thus serves as a cam, lifting and supporting the trigger while being shifted from the safety to the release position.

To adapt the trap to catching both rats and mice, the loop portion of the jaw is shown as having an intermediate cross bar 34, connecting the sides of the bail and in line with a cross depression 35, in the pan.

The parts are simple, strong and few and they can be easily assembled. After tacking the trip pan in position over the base and locating the spring coils at the end of the base, with the jaw portion 19, extending over and the end portions 18 beneath the base, the upright or back wall 11 may be slipped into position over the coils and the parts 12, 13, riveted together, through the base. Secured in this manner, the back wall is braced and rigidly held to the base. It is contemplated also that the entire frame may be molded in plastic.

The trap may be set with the movable trigger portion in position over the safety shoulder and then when it is ready for action, the trigger can be shifted from the safety position into the active relation, through the agency of the setting lever without danger of accidentally springing the trap.

What is claimed is:

1. A trap comprising a base, an upright having angularly extending substantially parallel projections engaged over one end of and secured to the base with space between said end of the base and the upright, a spring jaw having a coil portion located in said space between said angularly extending projecting portions of the upright, a trip platform pivotally supported on the base, a trigger extending from said platform through the upright, and a detent for said spring jaw mounted on the upright and engaged by said trigger, said trigger being pivotally connected

with the platform for lateral adjustment, a supporting shoulder on the upright engageable by said trigger in one laterally shifted position of the same and a setting lever pivoted on the upright and having a cam portion engageable beneath said trigger to support the latter while shifting it laterally from over said supporting shoulder.

2. A trap comprising a base, an upright support at one end of the same, a spring jaw supported at the foot of said upright and having a bail portion adapted to be raised to the top of said upright, a detent on said upright for releasably holding said bail in upraised relation, a platform pivotally mounted on the base, a trigger pivotally connected with said platform and projecting through the upright into position for holding engagement with said detent, a supporting shoulder on the upright for preventing releasing movement of said trigger and a setting lever pivoted on the upright for shifting said trigger laterally from supported relation over said shoulder.

3. A trap comprising a base, an upright support at one end of the same, a spring jaw supported at the foot of said upright and having a bail portion adapted to be raised to the top of said upright, a detent on said upright for releasably holding said bail in upraised relation, a platform pivotally mounted on the base, a trigger pivotally connected with said platform and projecting through the upright into position for holding engagement with said detent, a supporting shoulder on the upright for preventing releasing movement of said trigger, a setting lever pivoted on the upright for shifting said trigger laterally from supported relation over said shoulder, said lever having a cam portion for supporting said trigger during said shifting movement of the same.

4. A trap comprising a generally horizontal base, an upright of sheet material at one end of the same, said upright having an angularly bent bottom flange extended beneath the base and an integral portion above said bottom flange bent out at an angle and extended inwardly over the top of the base, fastenings extending through said base and through said flange and integral portion disposed below and over the top of the base and thereby rigidly securing said upright in upstanding relation at the end of the base, a spring jaw having a coil portion disposed at the end of said base and confined between said bottom flange and said inwardly extending portion of the upright and whereby said spring jaw is held against displacement, said spring jaw having a bail portion adapted to be raised to the top of the upright, a detent for said bail portion mounted on the upright, a trigger for holding said detent and means on the base for effecting release of said trigger from holding engagement with said detent.

FRANK DOVERSPIKE.
